UNITED STATES PATENT OFFICE.

JOHN J. NOETH, OF CHICAGO, ILLINOIS.

TIME-CONTROLLED MECHANISM.

1,209,748.

Specification of Letters Patent. Patented Dec. 26, 1916.

Application filed January 19, 1916. Serial No. 72,964.

To all whom it may concern:

Be it known that I, JOHN J. NOETH, a citizen of the United States, residing at Chicago, in the county of Cook and State of Illinois, have invented new and useful Improvements in Time-Controlled Mechanisms, of which the following is a specification.

The mechanism which is the subject matter of the present application for patent has been designed for automatically performing an operation and regulating the length of time before the operation is performed.

The invention has been illustrated in connection with an egg boiler, the receptacle containing the eggs being immersed in the boiling water and withdrawn therefrom after a predetermined interval of time. However, it is to be understood that this particular application of the invention is used for illustrative purposes only, and the invention is not limited thereto, various other applications and modes of use being obvious.

It is the object of the invention to provide a mechanism of the kind stated which is comparatively simple in construction, and withal reliable in operation, and to this end, the invention consists in a novel combination and arrangement of parts to be herein-after described and claimed.

In order that the invention may be better understood, reference is had to the accompanying drawings in which—

Figure 1 is a front elevation of the mechanism; Fig. 2 is a side elevation thereof, partly in section; Fig. 3 is an enlarged rear elevation of a fragment of the mechanism and Fig. 4 is a side elevation thereof; Fig. 5 is a plan view of a weight, and Fig. 6 is a front elevation showing the particular application of the invention.

Referring specifically to the drawings, 10 denotes a receptacle in which the eggs to be boiled are placed, said receptacle being positioned above a boiler 11 in which it is immersed and then withdrawn after a predetermined period of time. The receptacle is supported by a hoisting device, which may be a chain 12 trained over a pulley 13. Connection between the receptacle and the chain is made by a rod 14 connected to and extending from the receptacle and made fast at its upper end to one end of the chain. On the other end of the chain is hung a weight 15 of sufficient mass to overbalance the recep-

tacle and its contents. The weight is slidably mounted in a hollow upright 16 which also supports, at its upper end, the pulley 13, the upright being here provided with an opening 17 through which the chain passes. The weight is cored out hollow to receive the requisite amount of lead or other heavy material, which is introduced through a bottom hole fitted with a plug 18. The top of the weight has two ears 19 for attachment of the chain 12. The sides of the weight are sunk, as indicated at 20, to allow a lubricant to pass freely and prevent sticking of the weight in the upright 16.

One side of the weight 15 has a longitudinal recess in which seats and is made fast a rack bar 21 which faces outward and is designed to come in mesh with a pinion 22 mounted on a shaft 23 carried by a suitable support 24 mounted on the back of the upright 16, the latter having a slot through which the pinion projects so that it may come in mesh with the rack bar. The pinion 22 is loose on the shaft 23, and on the latter is fixed a ratchet wheel 25 engageable by a pivoted pawl 26 carried by the pinion, whereby the motion of the shaft in one direction only is transmitted to the pinion, and the latter is free to slip in one direction. The shaft 23 is connected by a train 27 of reducing gears to the shaft 28 of an electric motor 29.

The circuit of the motor 29 is automatically controlled by the following means: On a shaft 30, carried by the support 24, below the shaft 23, is fixed a rocker arm 31 carrying at its outer end an idler wheel 32 which is positioned to extend into the upright 16 through an opening in the back thereof, and thus come into the path of the weight 15. On the shaft 30 is also fixed a rocker arm 33 extending in the opposite direction from the rocker arm 31. The outer end of the rocker arm 33 is engaged by one end of a spring-pressed bolt 34 slidably mounted in a support 35 carried by the upright 16. The other end of the bolt engages a movable contact 36 opposite a stationary contact 37, to which contacts the circuit wires 38 of the motor 29 are connected. The contacts are normally separated and the motor circuit is thus open. Upon advancing the bolt 34 the contact 36 is carried over against the contact 37 to close the motor circuit, and upon retracting the bolt, the contacts separate and break the circuit, the contact 36 being re-

silent and having a normal tendency to spring away from the contact 37.

The upper end of the weight 15 is beveled on one side as indicated at 39 and when the same reaches the wheel 32, the shaft 30 is rocked in a direction to swing the arm 33 inward to advance the bolt 34 and thus close the motor circuit.

In the upright 16, above the weight 15, is mounted a stop bar 40 connected to and depending from the bottom of a scale bar 41 which extends from the top of the upright, and has side notches 42 engageable by a catch 43 for locking the scale bar in adjusted position and thus holding the stop bar fixed. The stop bar 40 is angular in cross section where it passes through a guide 44 in the upright, so that it is prevented from turning, and the upper end of the bar is threaded, as indicated at 45, to screw into the bottom socket of a rod 46 passing lengthwise through the scale bar 41. The upper end of the rod 46 protrudes through the scale bar and has a knurled head 47, and upon turning the rod by means of this head the stop bar may be adjusted lengthwise relative to the scale bar, the lower end of the rod into which the stop bar is screwed acting as a nut to raise or lower the stop bar, the latter being non-rotatable by reason of its angular cross section. The object of this adjustment is to adapt the mechanism to different designs of motors.

The scale bar 41 is pressed into engagement with the catch 43 by a spring 48 in the upright 16.

The operation of the mechanism may be summarized as follows: The scale bar 41 is first set for the period of time the receptacle 10 is to be kept immersed in the boiler 11, and the stop bar 40 is thus positioned the proper distance above the weight 15 to limit the height to which it may rise. The receptacle is now manually lowered into the boiler 45 until the weight reaches the bottom of the stop bar. As the receptacle is thus lowered, the weight rises, and its end 39 engages the idler wheel 32 to swing the rocker arms 31 and 33 to close the motor circuit as hereinbefore described. When the weight is elevated as described its rack 21 comes in mesh with the pinion 22. The motor 29 is now operating, and through the gearing 27 the shaft 23 is turned very slowly, this motion 50 being transmitted through the ratchet wheel 25 and the pawl 26 to the pinion 22, and as the latter is now in mesh with the rack bar 21, it will be evident that the weight is being allowed to slowly descend and the receptacle is being slowly withdrawn from the boiler. When the weight has descended a sufficient distance to disengage the rack bar 55 21 from the pinion 22, the weight is suddenly released and it drops by gravity down 60 to the bottom of the upright 16, thereby lift-

ing the receptacle 10 from the boiler 11. At the same time, the weight clears the idler wheel 32 and allows the arm 31 to swing forward to break the motor circuit, so that the motor 29 also stops. The length of time the receptacle is immersed depends on the position of the stop bar 28. The higher this bar is positioned the longer will be the period the weight's descent is checked or retarded by the motor until it is released and drops by gravity to elevate the receptacle. The function of the motor is to overcome that friction of the gear which the weight alone cannot overcome, both the weight and the motor acting to drive the gears against the frictional resistance thereto, and the weight alone being insufficient to cause this motion. A suitable friction device could be used to control the descent of the weight, but the motor and the gearing are the best combination for the reason that a correct timing to within a fraction of a second is possible.

Fig. 6 shows the grouping of several boiler units, only one motor 29 and speed reducing gearing 27 being employed, and the shaft 23 being common to all the units. Although the shaft 23 may be in constant operation, the timing of each unit will not be affected. Two units are shown for a boiling period of one minute, one unit for two minutes, and the remaining unit for three minutes. Assuming now that the unit set for one minute is placed in operation, and the one set for three minutes a few seconds later, then the dropping of the weight 10 of the first unit will not affect the second unit to the extent of cutting out the motor, as the weight of the second unit is still slowly descending and holding the circuit closed.

It will be understood that the motor 29 is not to be considered as a means for causing the descent of the weight 15. The function of the motor is to time the descent of the weight. As the receptacle 10 is lowered into the boiler 11 at the commencement of the operation, the weight 15 ascends, the pawl 26 now slipping around the ratchet wheel 25, the motor 29 not yet having picked up enough speed to turn the ratchet wheel 25 through the distance of one tooth. When the weight 15 reaches the stop bar 40 and is released, it has an immediate tendency to drop, but it is kept from doing so by the slowly rotating ratchet wheel 25, and the pawl engaging one of the teeth of the latter. The weight therefore cannot descend faster than the speed at which the ratchet wheel is turned, but being heavy it will descend as fast as the ratchet wheel allows it to do so.

I claim:

1. A time-controlled mechanism comprising a hoisting device having article-supporting means at one end, a weight connected to the other end of the hoisting de-

vice, an element for checking the descent of the weight, means for coupling the weight to said element upon elevating the latter, the ascent of the weight being variable, and said weight being freed from the checking element after having made a partial descent and thereafter being left unsupported and free to drop by gravity, and a motor for actuating the checking element controlled by the weight.

2. A time-controlled mechanism comprising a hoisting device having article-supporting means at one end, a weight connected to the other end of the hoisting device, an element for checking the descent of the weight, means for coupling the weight to said element upon elevating the latter, the ascent of the weight being variable, and said weight being freed from the checking element after having made a partial descent and thereafter being left unsupported and free to drop by gravity, an electric motor for actuating the checking element, a switch controlling the motor circuit, and actuating means for said switch controlled by the weight.

3. A time-controlled mechanism comprising a hoisting device having article-supporting means at one end, a weight connected to the other end of the hoisting device, an element for checking the descent of the weight, means for coupling the weight to said element upon elevating the latter, the ascent of the weight being variable, and said weight being freed from the checking element after having made a partial descent and thereafter being left unsupported and free to drop by gravity, an electric motor for actuating the checking element, a switch controlling the motor circuit, a swinging member in the path of the weight and actuated thereby, and operating means for the aforesaid switch connected to said member.

4. A time-controlled mechanism comprising a hoisting device having article-supporting means at one end, a weight connected to the other end of the hoisting device, an element for checking the descent of the weight, means for coupling the weight to said element upon elevating the latter, the ascent of the weight being variable, and said weight being freed from the checking element after having made a partial descent and thereafter being left unsupported and free to drop by gravity, an electric motor for actuating the checking element, a switch controlling the motor circuit, a rock shaft, a rocker arm carried by said shaft, a member carried by said arm and extending into the path of the weight, and operating means for the aforesaid switch carried by the shaft.

5. A time-controlled mechanism comprising a hoisting device having article-supporting means at one end, a weight connected to the other end of the hoisting de-

vice, an element for checking the descent of the weight, means for coupling the weight to said element upon elevating the latter, the ascent of the weight being variable, and said weight being freed from the checking element after having made a partial descent and thereafter being left unsupported and free to drop by gravity, an electric motor for actuating the checking element, a switch controlling the motor circuit, a rock shaft, 75 a rocker arm carried by said shaft, a member carried by said arm and extending into the path of the weight, a second rocker arm on the shaft, and an actuating member for the aforesaid switch engageable by said second 80 rocker arm.

6. A time-controlled mechanism comprising a hoisting device having article-supporting means at one end, a weight connected to the other end of the hoisting device, 85 a rack bar on the weight, a pinion engageable with the rack bar upon elevating the weight, the ascent of the latter being variable, a motor for driving the pinion in a direction to allow the weight to descend, the 90 pinion and the rack bar separating after the weight has made a partial descent, after which the weight is left free to drop by gravity, and motor-controlling means actuated by the weight.

7. A time-controlled mechanism comprising a hoisting device having article-supporting means at one end, a weight connected to the other end of the hoisting device, a rack bar on the weight, a pinion engageable 100 with the rack bar upon elevating the weight, the ascent of the latter being variable, an electric motor for driving the pinion in the direction to allow the weight to descend, the pinion and the rack bar separating after 105 the weight has made a partial descent, after which the weight is left free to drop by gravity, and motor-controlling means actuated by the weight.

8. A time-controlled mechanism comprising a hoisting device having article-supporting means at one end, a weight connected to the other end of the hoisting device, a rack bar on the weight, a pinion engageable with the rack bar upon elevating the weight, the 115 ascent of the latter being variable, an electric motor for driving the pinion in the direction to allow the weight to descend, the pinion and the rack bar separating after the weight has made a partial descent, after 120 which the weight is left free to drop by gravity, a switch controlling the motor circuit, and actuating means for said switch controlled by the weight.

9. A time-controlled mechanism comprising a hoisting device having article-supporting means at one end, a weight connected to the other end of the hoisting device, an element for checking the descent of the weight, means for coupling the weight to said ele- 125

- ment upon elevating the latter, the ascent of the weight being variable, and said weight being freed from the checking element after having made a partial descent 5 and thereafter being left unsupported and free to drop by gravity, a motor for actuating the checking element controlled by the weight, and a vertically adjustable stop above the weight.
- 10 10. A time-controlled mechanism comprising a hoisting device having article-supporting means at one end, a weight connected to the other end of the hoisting device, a rack bar on the weight, a pinion engageable with 15 the rack bar upon elevating the weight, the ascent of the latter being variable, a shaft on which the pinion is loosely mounted, a ratchet wheel fast on said shaft, a pawl carried by the pinion and engaging the ratchet 20 wheel, and a motor for driving the shaft, said shaft through the ratchet wheel and the pawl turning the pinion in a direction to allow the weight to descend, the pinion and the rack bar separating after the weight has 25 made a partial descent, after which the weight is left free to drop by gravity.
11. A time-controlled mechanism comprising a hoisting device having article-supporting means at one end, a weight connected to the other end of the hoisting device, a rack 30 bar on the weight, a pinion engageable with the rack bar upon elevating the weight, the ascent of the latter being variable, a shaft on which the pinion is loosely mounted, a ratchet wheel fast on said shaft, a pawl carried by the pinion and engaging the ratchet 35 wheel, a motor for driving the shaft, said shaft through the ratchet wheel and the pawl turning the pinion in a direction to allow the weight to descend, the pinion and the rack bar separating after the weight has 40 made a partial descent, after which the weight is left free to drop by gravity, and motor-controlling means actuated by the weight. 45

In testimony whereof I affix my signature.

JOHN J. NOETH.
